UNITED STATES PATENT OFFICE.

JOSEPH W. FISKE, OF NEW YORK, N. Y.

DESIGN FOR RIMS FOR FOUNTAIN-BASINS.

Specification forming part of Design No. 9,450, dated August 22, 1876; application filed August 9, 1876.
[Term of Patent 7 years.]

To all whom it may concern:

Be it known that I, JOSEPH W. FISKE, of New York, in the county of New York and State of New York, have invented certain Improvements in Designs for a Rim or Coping for Fountain-Basins, of which the following is a specification:

My design is fully illustrated in the accompanying photograph, to which reference is made.

This is a design for a rim or coping for a fountain-basin. It is made in sections, so that when united they will form a circle, the exterior surface being molded or paneled, or made in any desired ornamental style or form. At intervals the rim is provided with projections of a style to suit the form of the rim, which projections form pedestals for vases, as shown

in the photograph. Midway between these pedestals there is, on the outer face of the rim, an antique face, as an ornament.

In the photograph, I have shown a rim having four of the pedestals with vases on them, and four of the antique faces; but the number may be more or less, according to the size of the basin that it is desired to construct.

What I claim as my design is—

A rim or coping for fountain-basins, provided with the pedestals for vases, and the antique faces, substantially as shown and described.

JOSEPH W. FISKE.
